UNITED STATES PATENT OFFICE.

EMIL A. CUPPERS, OF NEW HAVEN, CONNECTICUT, ASSIGNOR TO SARGENT & CO., OF SAME PLACE.

DESIGN FOR A COFFIN-SCREW.

SPECIFICATION forming part of Design No. 12,033, dated November 16, 1880.

Application filed September 17, 1880. Term of patent 14 years.

To all whom it may concern:

Be it known that I, EMIL A. CUPPERS, of New Haven, in the county of New Haven and State of Connecticut, have invented a new 5 Design for Coffin-Screw; and I do hereby declare the following, when taken in connection with the accompanying drawing and the letters of reference marked thereon, to be a full, clear, and exact description of the same, and which 10 said drawing constitutes part of this specification, and represents a perspective view.

This invention relates to a design for an ornamental head for screws with particular reference to coffin-trimmings, such as screws for 15 securing the top or lifters for the lid; and it consists in the representation of a butterfly

with its wings spread as in beginning its flight.

A represents the screw, nail, or whatever it may be by which the ornament is to be attached, on which rests the body of the butterfly, its legs and wings extended as when beginning its flight.

I claim—

The design for coffin-screw head, consisting 25 of the representation of a butterfly with its wings spread as in the act of flight, as seen in the accompanying illustration.
